UNITED STATES PATENT OFFICE.

CHENOWETH HOUSUM, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CONDENSER.

1,309,803.

Specification of Letters Patent. Patented July 15, 1919.

Application filed December 11, 1915. Serial No. 66,646.

To all whom it may concern:

Be it known that I, CHENOWETH HOUSUM, a citizen of the United States, residing at Milwaukee, in the county of Milwaukee and 5 State of Wisconsin, have invented a certain new and useful Improvement in Condensers, of which the following is a specification.

This invention relates to improvements in the construction of steam condensers and 10 particularly to improvements in jet condensers of the high vacuum type.

An object of the invention is to provide a condenser which is simple in construction and efficient in operation. One of the more 15 specific objects of the invention is to provide a jet condenser of the high vacuum type in which the injection water is uniformly distributed in the condensing zone to produce rapid and efficient condensation of the 20 steam. Another object is to provide an efficient jet condenser in which the injection water is effectively delivered into and distributed in the condensing zone by gravity. A further object is to provide a high 25 vacuum jet condenser which will retain maximum efficiency throughout a considerable range of operating conditions.

A clear conception of an embodiment of the invention may be had by referring to the 30 drawing accompanying and forming a part of this specification in which like reference characters designate the same or similar parts in the various views.

Figure 1 is a transverse vertical section 35 through a jet condenser having the invention applied thereto.

Fig. 2 is a top view of the inner casing which forms the condensing zone of the condenser.

40 The condenser generally comprises essentially a vertical cylindrical outer casing 6 having a steam inlet 1 at the upper end thereof, a water inlet 2 at the side thereof near the top of the casing, an air outlet 3 somewhat below the water inlet 2, and a water outlet, not shown, near the lower end of the casing. While the casing 6 is disclosed as comprising a separate base and several detachable sections, this construction 45 is not essential. The inner casing 5 comprises a perforated annular upper wall forming a condensing zone and having a downwardly extending constricted portion forming an outlet 4 leading from the condensing

zone. The mid portion of the casing 5 is 55 provided with a flange 23 which engages an upper surface of the casing 6 and forms a support for the inner casing 5. An annular vertical wall 15 is formed integral with the flange 23 of the casing 5 and forms an annular water distributing pocket surrounding the perforated upper end of the casing 5.

The annular upper wall of the casing 5 is provided with several circular series of perforations or orifices 12, 13, 14, arranged one 60 series above the other and opening directly into the condensing zone. The orifices 12 of the upper series are preferably made somewhat larger and fewer in number than those of the intermediate series 13, while the orifices 13 of the intermediate series are somewhat larger and may be either fewer in number than or of like number as the orifices 14 of the lowermost series. The orifices of adjacent series are preferably arranged out of 65 vertical alinement with each other, giving them a staggered relation to each other. While the form of the invention disclosed embodies three series of orifices, there may be any number of these series, preferably 70 more than 2. The upper extremity of the perforated annular wall of the casing 5 is provided with a series of inwardly extending open troughs 11 which in the present disclosure are arranged substantially radially. Each of these troughs is provided with lower perforations or orifices 18 opening directly into the condensing zone. The troughs 11 are preferably arranged out of 75 vertical alinement with the adjacent orifices 12 of the casing 5. The orifices 12, 13, 14, and troughs 11 are preferably made of such 80 size and number that each series will tend to deliver substantially the same amount of water to the condensing zone that an adjacent series delivers.

The steam inlet 1 of the casing 6 is arranged in line with the upper open portion 85 of the casing 5, thus also serving as an inlet to the condensing zone. The water inlet 2 connects with an annular passage 19 which surrounds the annular wall 15 of the casing 5. The annular baffle wall 16 extends downwardly from the cover of the casing 6 and forms an annular air pocket at the extreme 90 upper end of the condenser. The constricted lower portion of the casing 5 which forms the outlet 4, projects downwardly into the 95

collection chamber at the bottom of the casing 6, to a point below the air outlet 3. The casing 6 and constricted outlet portion of the casing 5 coact to form an annular air pocket 10 for non-condensable vapors, which communicates directly with the air outlet 3. The air pocket 10 is connected with the air pocket 21 at the upper end of the condenser by means of one or more pipes 17.

10 Suitable water discharge pumps 7, which may be one or more in number depending upon the size of the condenser, are mounted in the lower portion of the casing 6 and are driven by a power shaft 8 mounted in bearings 20 located one at each side of the casing 6. These pumps 7 are adapted to discharge from the condenser the mixture of water of condensation, non-condensable vapors and condensing water which is delivered to the 15 lower portion of the casing 6 through the outlet 4. A suitable vacuum breaker 9, which may be of any of the well known types, either manually or automatically operated, is provided at one side of the casing 20 6.

25 During normal operation of the device, the exhaust steam flowing at high velocity is admitted to the condensing zone within the casing 5 through the steam inlet 1. The injection water admitted through the water inlet 2 flows around the annular distributing passage 19 and into the space directly adjacent the perforated wall of the casing 5. As the injection water flows through the orifices 12, 13, 14, and the troughs 11, it is delivered by gravity into the condensing zone in the form of streams. Some of the water passing through the troughs 11 is precipitated directly into the condensing zone 30 35 through the orifices 18, while that portion of the water passing through the troughs which is unable to pass through the orifices 18, is delivered over the inner ends of the troughs 11 to the central portion of the condensing zone. As the steam admitted through the inlet 1 passes downwardly through the condensing zone, it is compelled, due to the staggered arrangement of the troughs 11 and orifices 12, 13, 14, to take 40 45 a circuitous path between the streams delivered from the orifices and troughs. Due to the great number and the staggered relation of the streams of water admitted to the condensing zone, the steam is quickly condensed and the mixture of water and non-condensable vapor is delivered to the chamber at the lower end of the casing 6 through the outlet 4. The mixture of water and non-condensable vapor thus delivered to the lower chamber 50 55 of the casing 6 through the outlet 4, is discharged from the casing 6 by the pumps 7. Some of the non-condensable vapors escaping from the mixture flow into the pocket 10 from which they are withdrawn through 60 65 66 the air outlet 3.

The provision of the walls 15, 16, insures perfect distribution of the injection water to all portions of the condensing zone and prevents local injection of a greater portion of the water at the inlet side of the casing 5. 70 The air pipes 17 permit ready withdrawal by the air pump of any non-condensable vapors which may gather in the pocket 21. The portion of the casing 5 which forms the outlet 4 is preferably so formed that the 75 streams of water delivered through the orifices 14, substantially follow the contour of this portion of the casing. Due to the difference in head upon the water delivered through the troughs 11 and orifices 12, 13, 80 85 14, respectively, it will be noted that the streams delivered through the orifices 14 of the lower series will tend to pass inwardly to a greater extent than those delivered from the upper orifices. In order to prevent excessive inward travel and resulting violent impact of these streams upon each other, the lower portion of the inner perforated annular wall of the casing 5 is formed downwardly diverging, tending to deliver the 90 lower streams into the condensing zone in a direction along the adjacent surfaces of the wall forming the outlet 4. The streams delivered through the intermediate orifices 13 will be projected nearer the center of the 95 condensing zone than those delivered through the orifices 12. In order to prevent the formation of a dead space adjacent the upper end of the condensing zone, into which no condensing water is delivered, the troughs 100 11 are brought inwardly to a considerable extent. The provision of orifices 18 in the troughs 11 produces vertical streams of water which pass downwardly between the falling streams delivered from the orifices 12, 105 13, and tend to expose the inflowing steam to a maximum amount of cooling water surface.

It may be desirable under certain conditions of operation to reduce the quantity of injection water. This may readily be done by decreasing the supply entering the chamber 19 through the water inlet 2. The quantity of water thus admitted may be varied to a considerable extent without necessarily 110 reducing the efficiency of the condenser. In all cases, the injection water flows through the orifices and troughs under the impelling influence of gravity and hydrostatic head only, and with the condenser operating at 115 full load, substantially the same quantity of cooling water is entering the condensing zone through each series of orifices.

While the troughs 11 have been disclosed as formed integral with each other, it would 125 be within the scope of the present invention to form these as individual troughs secured to the casing 5, or to form the same in any other desirable manner. It should be understood that it is not desired to be limited to 130

the exact details of construction shown and described, for obvious modifications will occur to a person skilled in the art.

It is claimed and desired to secure by Letters Patent,—

1. In combination, a casing forming a condensing zone and having superposed series of orifices opening into said zone, the orifices of an upper series being larger than those of a lower series, a steam inlet for said casing, means for injecting water into said zone through said orifices, and an outlet from said casing.
2. In combination, a casing forming a condensing zone and having superposed series of orifices opening into said zone, the orifices of an upper series being fewer in number than those of a lower series, a steam inlet for said casing, means for injecting water into said zone through said orifices, and an outlet from said casing.
3. In combination, a casing forming a condensing zone and having superposed series of orifices opening into said zone, the orifices of an upper series being larger and fewer in number than those of a lower series, a steam inlet for said casing, means for injecting water into said zone through said orifices, and an outlet from said casing.
4. In combination, a casing forming a condensing zone and having superposed series of orifices opening into said zone, a plurality of troughs extending into said zone, a steam inlet for said casing, means for injecting water into said zone through said orifices and said troughs, and an outlet from said casing.
5. In combination, a casing forming a condensing zone and having a plurality of orifices opening into said zone, a plurality of

troughs extending into said zone, a steam inlet for said casing, means for injecting water into said zone through said orifices and said troughs, and an outlet from said casing.

6. In combination, a casing forming a condensing zone and having a plurality of orifices opening into said zone, a plurality of troughs each having a plurality of orifices opening into said zone, a steam inlet for said casing, means for injecting water into said zone through said casing and trough orifices, and an outlet from said casing.

7. In combination, a casing forming a condensing zone and having superposed series of orifices opening into said zone, the orifices of successive series being out of vertical alinement with each other, a plurality of troughs extending into said zone, said troughs being out of vertical alinement with adjacent casing orifices, a steam inlet for said casing, means for injecting water into said zone through said orifices and said troughs, and an outlet from said casing.

8. In combination, a casing forming a condensing zone and having superposed series of orifices opening into said zone, the orifices of successive series being out of vertical alinement with each other, a plurality of troughs extending into said zone, each of said troughs having a plurality of orifices opening into said zone and said troughs being out of vertical alinement with adjacent casing orifices, a steam inlet for said casing, means for injecting water into said zone through said casing and trough orifices, and an outlet from said casing.

In testimony whereof, the signature of the inventor is affixed hereto.

CHENOWETH HOUSUM.
